Primary Examiner — Mitchell I. Siegel(74) *Attorney, Agent, or Firm* — Banner & Witcoff, Ltd.(57) **CLAIM**

The ornamental design for a sporting implement, as shown and described.

DESCRIPTION

FIG. 1 is a rear view of a sporting implement showing our new design;

FIG. 2 is a left side view thereof; and,

FIG. 3 is a cross-sectional view at 3-3 in FIG. 1 thereof. The uneven-length broken lines immediately adjacent to the shaded area define the bounds of the claimed design and form no part thereof. The even-length broken lines depicting the remainder of the sporting implement show features that form no part of the claimed design.
